US00D536653S

(12) **United States Design Patent** (10) **Patent No.:** **US D536,653 S**
(45) **Date of Patent:** **** Feb. 13, 2007**

(54) **WHEEL**

(75) Inventors: **Kirk Rasmussen**, Wales, WI (US);
Willie G. Davidson, Delafield, WI
(US); **Louis Netz**, Grafton, WI (US)

(73) Assignee: **Harley-Davidson Motor Company Group, Inc.**, Milwaukee, WI (US)

(**) Term: **14 Years**

(21) Appl. No.: **29/221,821**

(22) Filed: **Jan. 21, 2005**

(51) **LOC (8) Cl. 12-16**

(52) **U.S. Cl. D12/211**

(58) **Field of Classification Search** D12/204-213;
301/37.101, 64.101, 65

See application file for complete search history.

(57) **CLAIM**

The ornamental design for a wheel, as shown and described.

DESCRIPTION

FIG. 1 is a front view of a wheel, showing our new design; and,

FIG. 2 is a perspective view thereof.

The broken line showing of the environment is for illustrative purposes only and forms no part of the claimed design.

1 Claim, 2 Drawing Sheets

FIG. 1

FIG. 2
